UNITED STATES PATENT OFFICE

GEORGE C. BATZ, OF TOPEKA, KANSAS
SPACING TOOL FOR HELICAL SPRINGS

Application filed April 30, 1931. Serial No. 533,971.

My invention relates to a spacing tool for helical springs. The object of my invention is to provide a spacing tool for helical springs comprising a rotatable bit arranged for insertion between the coils of a helical spring and certain driving means to rotate the spring during the rotation of the said bit.

Another object of my invention is to provide a machine tool of the kind described arranged to properly space the coils of a helical spring in one operation by the insertion of a rotatable bit between the coils of the spring and at the same time to rotate the spring against the bit.

These and other objects will hereinafter be more fully explained.

Referring to the drawings in which like characters apply to like parts in the different views:

Fig. 1 is an elevation of the spacing tool with a helical spring in position for spacing.

Fig. 2 is a sectional view of the tool taken on line 2—2 in Fig. 1. In this view the helical spring is removed and the mandrel is displaced from the operating position.

Fig. 3 is a section view taken on line 3—3 in Fig. 1.

Fig. 4 is an end view of the tool.

Fig. 5 is an elevation of a typical bit.

Fig. 6 is a side view of Fig. 5.

Fig. 7 is an enlarged elevation of one of the spring bearings supporting the roller.

Fig. 8 is a plan view of Fig. 7.

Fig. 9 is an end view of Fig. 7.

Fig. 10 illustrates the manner by which the coils of a helical spring having a comparatively small diameter are spaced.

Fig. 11 is an end view of Fig. 10.

A helical spring 1, in this instance, of the kind commonly used as equalizer springs on railway coach and freight trucks, is heated and placed on a stationary mandrel 2. This mandrel is pivotally carried at one end of the frame 2 as shown at A, and arranged to be swung outward as shown at B in Fig. 2.

At the other end of the mandrel a portion is removed to permit the engagement of the member 4, which is slidably mounted on the frame 3 at C and positioned relative to the

member 5, the latter rigidly connected to the frame 3, by means of the screw 6.

When the member 4 engages the mandrel 2 as indicated at D, the mandrel is rigidly positioned on the frame 3 and directly under the axis of a chuck 7.

The chuck 7 holds a bit 8 and is rotated by a shaft 9. The shaft 9 is carried vertically by the bearing 10 on the frame 3, and is suspended from the frame 3 by the springs 12. The shaft 13 of the air motor 14 has a square portion at E which engages the shaft 9.

The shaft 9 is slidable vertically to the shaft 13 on the square portion of the latter. The lever 9' engages the shaft 9 at F and fixes the relative vertical position of the shaft but does not affect its rotation. Means to hold the lever in a fixed vertical position is provided in the slot at G in Fig. 4.

When the lever 9' is positioned as shown in Figs. 1 and 4 the bit 8 is inserted between the coils of the spring 1 and rotated as desired by the motor 14.

The rotation of the bit spaces the coils and the width of the bit determines the coil spacing. The flat form of the bit allows its insertion between the coils to commence the operation and the rotation of the bit spreads the coils into the desired spacing as the helical spring is rotated on the mandrel 2.

To remove the spring 1, the lever 9' is released in the slot at A, thereby allowing the springs 12 to retract and raise the chuck 7, the member 4 is disengaged from the mandrel and the mandrel is swung outward as shown in Fig. 2.

A roller 15 having shafts 16 and 17 is supported by the bearings 16' and 17'. These bearings each have a lower portion at H, that pass vertically through the frame 3 and are affixed to a horizontal bar member 18 at J. The bar 18 extends through the frame 3 as shown at 1 and carries an air motor 20 at its left extremity, with reference to Figs. 1 and 2. The shaft 21 of the air motor is co-axial with and rigidly connected to the shaft 16 of the roller.

Spring bearings 22 and 23 trunnion the shafts 16 and 17 respectively. These bearings are identical and the enlarged details of

which are shown in Figs. 7, 8 and 9. The bearing block 24, is vertically slidable in the guide members 25. The guide members are rigidly connected to the frame 3. Spring members 26 5 provide the supporting means on the frame for the bearing blocks 24. The shafts 16 and 17 on the roller 15 and the entire assembly of bar 18 and motor 20 are carried by these blocks. This assembly has no other connection 10 with the frame 3 than that furnished by the slidable engagement of the bearing blocks 24 with the guides 25 and the upward thrust of the springs 26.

The force of the springs 26 hold the roller 15 in contact with the spring 1 and the rotation of the roller by the motor 20 provides the necessary rotation of the spring 1 around the mandrel 2.

In order to relieve the pressure of the roller 15 against the spring 1, for the purpose of removing the spring, I have provided an air cylinder 27, built integral with the frame, having a piston 28 and a rod 29, the latter connected to the bar 18 at K. When air pressure is admitted to the cylinder through the air line 30, the piston 28 is forced downward and the roller assembly is drawn downward. The springs 26 are compressed and the roller is spaced from the spring 1.

30 To operate this tool to properly space the coils of a helical spring:

The air cylinder 27 is charged and roller assembly is pulled downward against the springs 26. The member 4 is disengaged from the mandrel 2 and displaced as shown in Fig. 35 2. The lever 9' is released in the slot at G to permit the springs 12 to lift the chuck 7 into a higher vertical position.

40 A heated helical spring 1 is placed on the mandrel 2 and the latter is returned to the position indicated in Fig. 1 and secured by the member 4.

The spring 1 is moved horizontally on the mandrel 2 so that the space between the last 45 two coils at one end is directly under the bit 8. The lever 9' is forced downward to engagement in the slot at G and the bit 8 enters the space between the coils of the spring 1 as in Fig. 1. The air pressure is the cylinder 27 is released which allows the springs 26 to force the roller 15 against the helical spring 1. Air pressure is admitted to both motors 14 and 20. The former rotating the bit 8 and the latter 55 the roller 15.

55 The rotation of the bit 8 spreads the coils of the spring 1 as it is rotated by the roller 15, which rotation is continued until the entire spiral of the spring 1 has passed by the position of the bit 8.

This tool provides a simple and accurate method of coil spacing for helical springs. The spring may be driven past the bit 8 in one direction and then back again by reversing 65 the motor 20.

A modification of my invention is illustrated in Figs. 10 and 11.

This modification is used for helical springs of a comparatively small diameter.

A block 31, has a bore 32 extending 70 throughout. A smaller bore enters the bore 32 at right angles from the upper surface of the block. A helical spring 1' is positioned in the bore 32 so that the space between the last two coils at one end is directly under 75 the bore 33.

A bit 8' in a chuck 7', the latter rotated in a manner similar to the chuck 7, is lowered into the bore 33 to spread the coils of the spring 1'. The spring 1' is rotated by hand 80 until its entire spiral has traversed the point of the bit 8'.

The action of the bit 8' is the same as that described for the bit 8 and the bore 32 prevents distortion of the coils. 85

Such modification may be employed as lie within the scope of the appended claims and what I claim as new and desire to secure by Letters Patent is:

1. In a tool of the kind described, the combination of a bit rotatable at 90 degrees to a stationary mandrel, the bit inserted to spread the coils of a helical spring carried by the said mandrel, a roller as driving means to rotate the spring. 90

2. In a tool of the kind described a bit and a mandrel, the bit mounted vertically above the mandrel and rotated by a chuck, the mandrel rigidly positioned and functioning as holding means for a helical spring, means to insert the bit between the coils of the spring and means to rotate the spring on the mandrel for the progression of the spring by the position of the bit. 100

3. In a tool of the kind described, as means to rotate a helical spring on a mandrel a roller assembly comprising a roller, driving means for the roller and a bar member as carrying means for the roller and its driving means, certain spring members as means to thrust 110 the roller against the helical spring and an air cylinder to compress the springs and release the roller.

4. In a tool of the kind described, a mandrel, means to rotate a helical spring on the 115 mandrel in association with a rotatable bit, a roller assembly, said roller assembly trunnioned on a bar, by means of rigid bearings, and also trunnioned in spring bearings, the last said bearing supported on a frame by 120 certain springs, means to compress the springs.

5. In a tool of the kind described, a frame, a rotatable bit positioned in a chuck, a stationary mandrel, the bit positioned on the 125 frame at right angles to the mandrel, certain motive power to rotate the chuck, the mandrel rigidly connected to the frame and functioning as holding means for a helical spring, a roller adjustably mounted on the frame in 130

the place of the mandrel, certain motive power to turn the roller and certain means to space the roller from the mandrel.

6. In a tool of the kind described, an adjustable roller assembly, a mandrel, a chuck carrying a bit and a frame, the roller assembly adjustably spaced to the mandrel on the frame and the bit adjustably positioned to the mandrel, the mandrel functioning as an axis of rotation for a helical spring, means consisting of certain motive power on the roller assembly to rotate the spring and certain driving means to rotate the chuck, to space the coils of the helical spring.

15 In testimony whereof I affix my signature,
GEORGE C. BATZ.
